UNITED STATES PATENT OFFICE.

FRANK W. SHUPERT, OF SANFORD, FLORIDA.

SUPERHEATER UNIT.

Application filed April 20, 1925. Serial No. 24,640.

This invention relates to improvements in superheater units.

The primary object of this invention is the provision of a novel type of superheater 5 unit.

A further and important object of this invention is the provision of a compact type of superheater unit which has a large heating surface, and which may be placed in a 10 flue or other heating casing in such manner as to permit an unobstructed draft to take place through the flue.

A further object of this invention is the provision of an improved superheater unit 15 embodying a novel and compact construction which will permit of the unretarded flow of steam in a thin sheet through the superheater, so that the same will be exposed uniformly to the heat surrounding the unit.

20 A further object of this invention is the provision of a novel type of superheater unit utilizing stock materials.

Other objects and advantages of this invention will be apparent during the course 25 of the following detailed description.

In the accompanying drawings, forming a part of this specification, and wherein similar reference characters designate corresponding parts throughout the several 30 views,

Figure 1 is a perspective view of the improved superheater unit.

Figure 2 is a longitudinal cross sectional view taken through the superheater unit 35 showing the application of the same in the flue of a fire-box.

Figures 3, 4, 5 and 6 are cross sectional views taken substantially on their respective lines in Figure 2 of the drawings.

40 Figures 7, 8, 9, 10, and 11 are sectional and perspective views illustrating the successive steps used in forming the superheater unit from stock sizes of circular pipe.

In the drawings, wherein for the purpose 45 of illustration is shown the improved superheater and the various steps by which the same is produced, the letter A may generally designate the improved superheater, which is adapted for positioning in a flue B 50 of a furnace construction C.

The furnace C may be of the usual type, including a smoke box 15 in which one end of the flue B rests; the flue B providing a 55 passageway 16 therethrough of uniform diameter, which outlets at its rear end into the

fire box compartment, in accordance with any of the well known constructions.

The superheater unit A is adapted for placement in the passageway 16 of the flue B facing the fire-box, with certain inlet and 60 outlet connections extending into the smoke box.

The construction of the improved superheater A may best be described by taking up the sequence of the steps used in the making of the same. It is preferred to take a pair of lengths of circular pipe 20, substantially of the cross section illustrated in Figure 7, and of any approved length, and roll the same into hollow concavo-convex 65 formation between male and female rollers 21 and 22. This produces of each pipe length a concavo-convex shaped piece such as is illustrated in Figure 9, rolled into segmental form and providing the spaced 70 concavo-convex walls 24 and 25 connected by the arcuate edge portions 26, providing a shallow or thin passageway 27 of concavo-convex cross section, and extending the length of each piece. The wall 24 is con- 75 centric with the wall 25, although they are struck from different radii with the radius of the wall 24 less than the radius of the wall 25. The pair of pipe sections which form the main part of the superheater in 80 lieu of rolling to the concavo-convex form may be pressed to such form.

The fire-box facing ends of the arcuate pieces may then be welded closed, as illustrated at 30 in the drawings, and tapered to 85 a sharp edge 31 which faces the fire-box end in the flue passageway. This end of each of the sections of rolled or pressed pipe is thus made steam tight, and provides a non-baffling surface exposed to advancing heated 90 gases, which tends to divide the heated gases into definite streams, without unduly restricting the same, and as will subsequently appear. The next operation is that of cutting an elongated communicating passageway or port 33 in each of the arcuate sections 34 or 35. These ports are placed in the crown of the walls 25 of each of the sections 34 and 35, parallel with the respective sections, and immediately adjacent 95 to the closed end 30. The ports 33 are preferably cut with an oxy-acetylene torch, although other means of cutting the same may be used. The ports 33 of the two sections 34 and 35 are preferably of the same dimension 100 to the closed end 30. The ports 33 are preferably cut with an oxy-acetylene torch, although other means of cutting the same may be used. The ports 33 of the two sections 34 and 35 are preferably of the same dimension 105 to the closed end 30. The ports 33 are preferably cut with an oxy-acetylene torch, although other means of cutting the same may be used. The ports 33 of the two sections 34 and 35 are preferably of the same dimension 110 to the closed end 30. The ports 33 are preferably cut with an oxy-acetylene torch, although other means of cutting the same may be used. The ports 33 of the two sections 34 and 35 are preferably of the same dimension

sion, and located in the same relation in their respective sections. This step in the method of making the superheater is well illustrated on the section 34 illustrated in Figure 10 of the drawings.

The next operation is preferably that of connecting the concavo-convex hollow sections 34 and 35, at the ports 33, so as to communicate the passageways 27 of the sections 34 and 35. This operation is preferably accomplished by placing a pair of spacers 40 and 41 between the crown portions of the walls 25 of the sections 34 and 35, at opposite ends of the ports 33; the spacers 15 preferably being solder. The sections 34 and 35 are held in such relation with the ports 33 aligning by means of clamps 45 and 46, of any approved character, and the sections are now in position for the welder. 20 Either oxy-acetylene or electric arc is used to flow the metal in about the ports 33, and such welding is accomplished so that the ports 33 are not closed up, and the metal is flowed peripherally about the ports to 25 provide a single communicating port between the passageways 27 of the sections 34 and 35. This communicating port is of course steam tight, and guides the steam in its flow from one section 34 to the other 30 section 35. The clamps are then removed and the superheater unit is practically complete.

At the open ends of the sections 34 and 35, the inlet and outlet tubular connections 35 50 and 51 are respectively welded or secured to the sections 34 and 35. The tubing from which these connections 50 and 51 are formed is preferably 1½" in diameter, less than the original diameter of the pipe from 40 which the sections 34 and 35 are formed. These leads are either secured to the sections before their connection about the ports 33, or after such connection. To accomplish the connection of these leads to the sections 45 34 and 35, the arcuate or concavo-convex sections 34 and 35 are swaged by machinery, and are butt welded to the tubing 50 and 51, and reinforced with electric arc or oxy-acetylene welding. The leads 50 and 51 50 and their respective sections are preferably made up in straight pieces, and the leads are bent into obtuse angular relation 55 subsequent to their welding to their respective sections, at any angle to suit. It can be readily understood from Figures 1 and 5 of the drawings that the leads 50 and 51 are welded at approximately points 55 to the open swaged ends of the concavo-convex cross sections 34 and 35.

60 The superheater unit A when thus complete has the sections 34 and 35 connected at the fire-box ends of said sections, and incident to the fact that this connection is at the crown of the sections 34 and 35, the unit A really provides four radially extend-

ing vanes, which are well illustrated in the end view Figure 3, with the fire-box facing edges 31 in position to readily divide the stream of heated gases into four streams. The superheater unit A when in the passageway 16 of the heater flue B divides the passageway into four parallel ways 60, 61, 62 and 63, through which the heated gases flow to uniformly heat the large exposed external surface of the sections 34 and 35, and to uniformly heat the thin stream of flowing steam which first passes through the section 34 and through the communicating port into the section 35 and exits therefrom through the connecting pipe 51. It is to be 70 noted that rearwardly of the communicating port, the sections 34 and 35 are spaced, as at 65, and this provides additional heating surface.

It can readily be understood from the foregoing that a novel type of superheater has been provided, which may be economically manufactured to superheat steam in an efficient manner, by uniformly heating the superheated steam in a confined space, 80 while the steam is flowing in a thin sheet through the superheater. By reason of the novel provision of the superheater unit, a maximum heating surface is provided therefor in the confined space within the heat 85 conducting flues of the furnace, and by reason of the sharp dividing edges and the parallel unobstructed passageways 60 to 63 inclusive, the superheater does not obstruct the draft, and hence there will be less soot 90 and cinders collect than is ordinarily the case with complicated forms of superheaters, which ignore the obstructing effect of a draft.

Various changes in the shape, size, and arrangement of parts may be made to the 105 form of invention herein shown and described without departing from its spirit or the scope of the claims.

I claim:

1. As an article of manufacture a superheater unit comprising a pair of substantially concavo-convex hollow sections longitudinally connected at their convex sides providing narrow passageways extending longitudinally therethrough, said passageways 110 at similar ends of said sections being open and at the opposite ends of said sections having a communicating port.

2. As an article of manufacture a superheater unit comprising a pair of substantially concavo-convex sections each providing narrow concavo-convex shaped passageways extending longitudinally thereof, said concavo-convex sections only being connected adjacent their outer ends at the convex 120 sides thereof and through said connection providing a port communicating the passageways thereof, and inlet and outlet means for the opposite ends of said sections.

3. As an article of manufacture a super-

heater unit comprising a pair of hollow concavo-convex elongated sections providing relatively narrow concavo-convex passageways extending longitudinally thereof, the 5 sections at similar ends of each being closed and at the outer edges thereof providing sharp stream dividing edges, said sections adjacent said stream dividing edges being connected at the crown portions of the convex sides and through said connection providing a communicating port between the 10 passageways of said sections, said sections opposite the above mentioned closed ends having inlet and outlet means for the passageways thereof.

4. As an article of manufacture a superheater unit comprising a pair of substantially concavo-convex hollow sections each providing elongated passageways there- 20 through which are shallow as to depth and wider than the depth throughout the length thereof, means connecting said sections at the convex sides thereof adjacent similar ends of the same and through said connection providing a port extending between the 25 passageways, said sections at said ends being closed and at the opposite ends being open to provide an inlet way into one section and an outlet way from the other section.

5. As an article of manufacture a superheater unit comprising a pair of elongated tubes crescent shaped in cross section and providing crescent shaped passageways extending longitudinally therethrough, said 35 sections at the outer ends thereof having the passageways thereof communicated by a port and at the opposite ends thereof having inlet and outlet openings respectively, said sections being connected at their convex sides 40 between the longitudinal edges thereof to space the upper and lower portions of said sections above and below the connection thereof and provide passageways in a flue when the superheater is inserted therein.

6. As an article of manufacture a superheater substantially X-shaped in cross sec-

tion including a plurality of elongated radially disposed portions connected at the longitudinal center, and extending therefrom in spaced relation and providing passageways therethrough with communicating ports and inlet and outlet openings.

7. As an article of manufacture a superheater unit comprising a pair of elongated tubular sections, each of which are substantially crescent-shaped in cross section with crescent shaped passageways extending longitudinally therethrough, each section providing a convex side and a concave side, said sections at the convex sides thereof along 55 the medial longitudinal line having a connection with a transverse communicating port therethrough so as to face the concave sides of said section outwardly, said sections having inlet and outlet openings there- 60 through at the ends opposite said communicating port.

8. As an article of manufacture a superheater unit comprising a plurality of elongated tubular sections connected in a substantially X-shaped relation providing passageways therethrough with inlet and outlet openings and a connecting port for the passageways, said sections at the ends thereof opposite the inlet and outlet openings being 70 closed and being tapered to provide chisel edges in an X-shaped relation.

9. In a superheater unit the combination of a pair of elongated substantially concavo-convex hollow sections having connection 80 longitudinally at convex sides substantially midway between the opposite longitudinal edges of each whereby the said sections from said connection diverge in opposite directions with respect to each other, the said sections longitudinally therethrough having narrow and relatively wider elongated passageways having inlet and outlet openings therefor and a communicating port remote 85 from the inlet and outlet openings of said 90 passageways.
